UNITED STATES PATENT OFFICE.

LEWIS A. McDOWELL, OF LUVERNE, MINNESOTA

SPARK-PLUG.

1,247,978.

Specification of Letters Patent. Patented Nov. 27, 1917.

Application filed April 16, 1917. Serial No. 162,260.

To all whom it may concern:

Be it known that I, LEWIS A. McDowell, a citizen of the United States, and a resident of Luverne, in the county of Rock and State of Minnesota, have invented certain new and useful Improvements in Spark-Plugs, of which the following is a specification.

The present invention relates to ignition means for internal combustion engines.

The spark plug presented in my U. S. Patent #1,196,566, August 29, 1916, includes a split collar threaded into the body of the plug and provided with a depending U-shaped member carrying the lower electrode. This collar is provided to afford means for varying the relation of the electrodes as stated in the patent, but it has been found that the device suffered from the fact that the collar failed to remain fixed after being adjusted due to the fact that the vibration of the engine tends to cause the collar to unturn from the plug and thereby increase the space between the electrodes.

5 The present invention has, therefore, for its primary object the provision in a spark plug of this type of means for preventing the above-recited evil.

10 The invention is a distinct improvement over the device disclosed in my patent above mentioned, inasmuch as the electrode carrying collar can be freely screwed into the body yet can be unscrewed only by application of a wrench and cannot be displaced by vibration of the motor.

15 The invention will be clearly understood from the following description, reference being had to the accompanying drawings which form a part of this application and in which like characters of reference indicate corresponding parts throughout the several views, of which,—

Figure 1 is a longitudinal section of a spark plug constructed in accordance with 15 the invention;

Fig. 2 is a plan of the electrode-carrying collar;

Fig. 3 is an elevation of the same;

Fig. 4 is a horizontal section of the spark 20 plug taken on the line A—A of Fig. 3; and

Fig. 5 is an elevation of the insulating core.

Referring, now, to the illustrations, the plug illustrated includes a shell, 5, threaded on its lower end as at 6, adapting it to be 55 readily screwed into the cylinder as usual. The shell, 5, has a bore, 7, extending therethrough which bore is threaded at its lower end as at 8, to receive an externally-threaded collar, 9, having a depending U-shaped 60 member 10, carrying in its web an upwardly extending electrode, 11. The collar is split longitudinally, as at 12, adjacent one of the arms of the member, 10, affording a relatively large segmental portion, 13, which is 65 free to expand and engage, at its edge, 14, the shell to prevent unturning of the collar. Obviously, with the slot, 12 positioned as illustrated, the collar is right threaded but if it were left threaded the slot would necessarily be adjacent the opposite arm of the member, 10.

70 It is evident that this arrangement permits the collar to be screwed readily into the shell but experience and many tests have 75 proven that the vibration does not tend to screw the collar upwardly but will screw it downwardly unless means are provided different from the construction disclosed in my prior patent.

75 16, is the insulating core inclosed by the shell and held therein by a gland nut, 17, threaded into the body. 18, is the center electrode which is carried by the insulator, 16, and supported thereby in spaced relation 80 to the lower electrode.

Having thus described my invention what I claim as new and desire to secure by Letters Patent of the United States is,—

85 In a spark-plug, a shell internally-threaded at its lower end, an upper electrode, and a collar threaded into the shell and provided with a U-shaped depending member carrying an electrode to coat the upper electrode, the collar being of yieldable material 90 and split adjacent one of the arms of said member, the free edge of the collar being engageable with the shell to prevent unscrewing of the collar.

95 In testimony whereof, I have hereunto set my hand this 5th day of April, 1917.

LEWIS A. McDOWELL.
